UNITED STATES PATENT OFFICE.

JOHN A. COCKER, OF JOLIET, ILLINOIS, ASSIGNOR TO THE AMERICAN STEEL AND WIRE COMPANY OF NEW JERSEY, A CORPORATION OF NEW JERSEY.

FENCE-MAKING MACHINE.

Application filed July 13, 1925. Serial No. 43,170.

This invention relates to fence making machines and more particularly to a machine for making a woven lawn fence consisting of longitudinal line or cable strands and transverse picket wires having arched tops, and has for its object the provision of such a machine which will be entirely automatic in operation.

Heretofore fence such as is made by this machine has been made on manually controlled machines and the picket wires were fed into place by hand. Such machines were necessarily slow in operation and required considerable skill to operate, resulting in a comparatively high cost of manufacture and an article which was not uniform in quality.

The present invention eliminates the manual control and provides an entirely automatic machine, thereby permitting greater speed in operation, and resulting in a material reduction in the cost of manufacture, and providing a product uniform in quality.

In the drawings—

Fig. 1 is a top plan of a fence making machine embodying my invention.

Fig. 2 is a side elevation thereof.

Fig. 3 is a rear end elevation thereof.

Figs. 4 and 4^a combine to form an enlarged side elevation.

Fig. 5 is a partial side elevation opposite to that of Figs. 4 and 4^a.

Fig. 6 is a sectional elevation through the twisting spindle operating mechanism.

Figs. 7 and 8 are detail sectional elevations through one of the twisting spindles.

Figs. 9, 10, and 11 are elevations of the twisting spindle operating mechanism showing its different operating positions.

Fig. 12 is a partial enlarged side elevation showing the control cam for the picket feeding and crimping mechanism.

Fig. 13 is an enlarged top plan of the mechanism of Fig. 12.

Fig. 14 is a sectional elevation on the line XIV—XIV of Fig. 12.

Figs. 15 and 16 are plans taken at 90 degrees of the rotary picket guide.

Figs. 17, 18, 19, and 20 are elevations taken on the lines XVII—XVII, XVIII—XVIII, XIX—XIX, and XX—XX of Fig. 16.

Figure 21 is an enlarged detail fragmentary plan showing the picket feed mecha-

nism, shear and prebender for the short pickets.

Fig. 22 is a sectional elevation on the line XXII—XXII of Fig. 21.

Fig. 23 is a detail elevation of the ratchet operating mechanism of the short picket prebender.

Fig. 24 is a sectional elevation through the prebender on the line XXIV—XXIV of Fig. 22.

Fig. 25 is a sectional elevation similar to Fig. 24 taken at substantially ninety degrees to that of Fig. 24.

Fig. 26 is a top plan, partly broken away, of the short picket prebender.

Fig. 27 is a fragmentary sectional elevation showing the rotary picket guide locking mechanism.

Fig. 28 is an enlarged fragmentary plan showing the short picket arch forming mechanism.

Fig. 29 is an elevation on the line XXIX—XXIX of Fig. 28.

Figs. 30 and 31 are detail fragmentary views showing the mounting of the short picket arch forming mechanism.

Fig. 32 is an enlarged fragmentary plan showing the long picket manipulating mechanism for placing the pickets in an arch forming mechanism.

Fig. 33 is a sectional elevation on the line XXXIII—XXXIII of Fig. 32.

Fig. 34 is a transverse sectional elevation showing the mechanism of Fig. 33.

Fig. 35 is an enlarged detail elevation of the long picket advancing mechanism.

Fig. 36 is a similar view to that of Figure 35 taken oppositely.

Fig. 37 is a plan of the long picket bending mechanism.

Fig. 38 is a sectional elevation on the line XXXVIII—XXXVIII of Fig. 37.

Fig. 39 is a plan of the picket bending mechanism in closed position.

Fig. 40 is a sectional elevation on the line XI—XL of Fig. 39.

Fig. 41 is a sectional elevation showing the operating mechanism of the long picket bending mechanism.

Fig. 42 is a sectional elevation taken on the line XLII—XLII of Fig. 41.

Fig. 43 is a sectional plan of the pull-out drum.

Fig. 44 is a fragmentary detail sectional elevation of the pull-out drum.

Fig. 45 is a diagrammatic plan of a section of fence made by the machine of this invention.

Referring more particularly to Fig. 45 of the drawings, a section of the fence made on the machine of this invention is shown. The letter *a* designates the line or cable strands of the fence, each of which is composed of two wires twisted together, and the letter *b* designates the long pickets which extend the full height of the fence and are mounted between the twists of the line strands. Alternating with the full length pickets *b* are short pickets *c*, which may vary in height, but which are shown in the present instance extending only approximately one-half the height of the fence. Both the long and short pickets *b* and *c* are crimped their entire length and have their upper ends reversely bent to form arches and their free ends are inserted between the twists of the line strands to hold them in position.

Now referring to the remainder of the drawings illustrating the automatic machine of this invention for fabricating the above described fence, the numeral 2 designates the main frame and 3 a bed plate. Located at the rear of the main frame 2 is a line wire guide rack 4 having suitable sheaves 5 for guiding the line wire to the machine. At the forward or machine end of the rack 4 a pair of vertically spaced rollers 6 and 7 are journaled in the vertical posts 8 of the rack, and below the lower roller 7 is a sheave shaft 9 having a plurality of feed or guide sheaves 10 thereon. The line wires are adapted to be trained over the sheaves 5 of the rack then down under the rollers 7 and then over the upper roller 6, thence down and under the sheaves 10 to the twisting spindles 11 of the machine.

The spindles 11 are rotatably mounted in a suitable spindle carrying bar 12 and each is provided with a pinion 14 integrally formed thereon intermediate its ends. The pinions 14 of the spindles 11 are each in mesh with the top face 15 of a double faced rack bar 16 which has its lower face 17 in mesh with a mutilated gear 18 carried on a shaft 19 journaled in suitable brackets 20. Each of the spindles 11 is provided with a pair of spaced longitudinally extending openings 21 for the passage of the line wires.

The shaft 19 also carries a pair of combined ratchet and trap drums 22, one on each side of the gear 18, and a pair of swinging or rock arms 23 are also mounted on the shaft 19 adjacent each of the members 22. The arms 23 are each provided with ratchet dogs 24 adapted to engage the ratchet wheel portions 22^a of the member 22 and with dog levers 25 which are provided with rollers 26 adapted to ride on the trap

drum portions 22^b of the members 22 and to be engaged in the traps 27 in the drums. The dog portions 28 of the levers 25 are adapted to engage in ratchet teeth 29 cut on the mutilated gear 18.

The dog levers 25 extend right and left-hand, and the teeth 29 are cut right and left-hand, so that when the rollers 26 are trapped, the gear 18 will be moved first in one direction and then in the other when the rock arms 23 are rocked or oscillated, thereby causing the spindles 11 to revolve in first one direction and then the other.

The arms 23 are adapted to be rocked or oscillated by a connecting rod 30 which is connected to the crank 31 of a shaft 32 extending longitudinally of the machine frame and journaled in bearings 33. The shaft 32 is geared to the main power shaft 34 of the machine by gears 34^a and 34^b.

The ratchet wheel portions of the members 22 are each provided with seven teeth 22^y, so that at each revolution of the shaft 32 the members 22 will be revolved one-seventh of a turn, due to the dogs 24 engaging the teeth 22^y. The drum portions of the members 22 are each provided with two of the trap depressions 27 spaced a short distance apart. The rollers 26 ride on the periphery of the drums until one of the depressions 27 is reached, when they are pulled into the depression causing the dogs 28 to engage the teeth 29 on the gear 18. The traps 27 are so spaced in the pair of members 22 that one dog lever 25 will be riding on the periphery of the drum, while the other lever is in engagement with the gear and vice-versa. Therefore, the gear 18 will be moved first in one direction and then in the opposite direction, with a pause or rest intermediate its movement in either direction, due to the transition of the dog lever 25 from one trap 27 to the next.

The line or cable strands pass from the spindles 11 to the pull-out drum B. The pull-out drum B comprises a central shaft 35 revolvably mounted in suitable bearings in the frame of the machine, and having a plurality of supporting disks 36 keyed thereon. The disks 36 have their peripheries recessed or slotted at spaced intervals for the reception of longitudinally extending bars 38 forming the cage of the drum and supporting the rigid and movable gripping jaws 39 and 40, respectively. The movable jaws 40 have U-shaped lower ends which fit over operating rods 41 mounted for sliding movement in supports 42 and the disks 36. The rods 41 are provided with suitable stops 43 adapted to engage the jaws 40 and rock said jaws when said rods are shifted lengthwise. Suitable coiled springs 44 are mounted on the rods 41 and tend to normally hold said rods 41 and jaws 40 in open position. The rods 41 are provided with rollers 45 at one

end and suitable cams 46 are mounted on brackets 47 at each end of the drum and are engaged by the rollers 45. As the rollers 45 engage or ride upon the cams 46, they shift the rods 41 against the tension of the springs 44, thus closing the jaws 40 so as to grip the line or cable strands of the fence as the drum is revolved.

The drum B is adapted to be revolved to pull the line or cable strands through the machine as they are twisted, and said drum must remain at rest when the feed wires are not being twisted so as to permit the feed of the picket wires. In order to accomplish this step by step movement of the drum, the shaft 35 is provided with ratchet wheels 48 at each end, which are keyed to the shaft and are adapted to be engaged and rotated by dogs 49 mounted on one arm of bell crank levers 50 which are pivotally mounted on the shaft 35. The levers 50 are adapted to be rocked by cams 51 mounted on stub shafts 52 journaled in suitable bearings in the main frame of the machine. The shafts 52 also carry gears 53 which are in mesh with pinions 54 on a shaft 55 which in turn is driven through gears 56 and 57 from the shaft 32. The gearing is such that the cams 51 will engage the levers 50 so as to move the drum in exact time with the coiling spindles. That is, the pull-out drum will revolve only when the coiling spindles are in operation, and will be at rest when the spindles are at rest.

The picket wires are adapted to be fed into the machine by a pair of combined crimping and feed rolls 60 and 61 mounted on shafts 62 and 63, which shafts are geared together by gears 64 and 65 mounted on the respective shafts and in mesh with each other. The picket wire is adapted to be trained from a suitable overhead guide sheave (not shown) under a guide sheave 66 and through a guide tube 67 into the bite of the rolls 60 and 61. As the wire passes through the rolls 60 and 61 it enters a second guide tube 68 which extends into the machine into close proximity to a bending head 120.

The picket feed rolls 60 and 61 are adapted to be automatically set in motion for predetermined times to feed the long and short picket wires by meshing or engaging a clutch composed of disks 70 and 71 mounted on a shaft 72. The clutch disk 70 is the driving member and is mounted for free rotation on the shaft 72 and is provided with an integrally formed gear portion 73 which meshes with a gear 74 on the roller shaft 63. The clutch disk 71 is the driven member and is keyed on the shaft 72 for sliding movement. The shaft 72 is connected by gears 75 and 76 with a shaft 78 which in turn is connected by gears 79 and 80 with a power shaft 81, which is connected by gears 82—83,

shaft 84 and gears 85—86 with the main drive shaft 34 of the machine.

The movement of the clutch disk 71 into engagement with the disk 70 is controlled by means of a substantially U-shaped lever 87 pivotally mounted at 88 on a bracket 89 and having a yoke portion 90 engaged in a groove in the clutch disk 71 and having its lower leg portion secured to a spring 91 which normally pulls said lever downwardly so as to move the clutch disk 71 out of engagement with the disk 70. The other or upper arm of the lever 87 is provided at its end with a roller 92 which rides on the periphery of a cam disk 93 mounted on a shaft 94. The disk 93 is provided with a pair of adjustable cam surfaces 95 and 96 which may be adjusted around the periphery of the disk to vary their length. In operation, when the cam surfaces 95 and 96 engage the roller 92 on the lever 87, the lever will be rocked about its pivotal mounting 88 so as to force the clutch disk 71 into engagement with the disk 70 so as to drive the shaft 63 through the gears 73 and 74, and thereby operate the combined feed and crimping rolls 60 and 61. The cam surface 95 is materially shorter than the cam surface 96 so that the clutch disk 71 will be held into engagement with the clutch disk 70 for a shorter length of time by the action of the cam surface 95, than by the cam surface 96, thus actuating the feed and crimping rolls for corresponding varying lengths of time, and consequently varying the length of the picket wires fed into the fence to form short and long pickets.

The shaft 94 receives its power from the shaft 78 through a beveled pinion 98 on the shaft 78 which meshes with a beveled gear 99 on the shaft 94.

The speed of the cam disk 93 and arrangement of the cam surfaces 95 and 96 are such, that the clutch disks 70 and 71 will be forced into engagement to drive the feed and crimping rolls 60 and 61 only when the pull-out drum and coiling spindles are stationary.

The picket wire is adapted to be guided across the fence and between the wires forming the line or cable strands by a rotary picket wire guide 100. The guide 100 is rotatively mounted in suitable bearings immediately over the forward ends of the coiling spindles 11, and is provided with guide ribs 101, 102, 103, and 104, which are cut away to clear the spindles 11 as the guide is rotated. The ribs 101 and 102 are slotted longitudinally, as at 105, to provide passage for the long picket wires, while the ribs 103 and 104 are cut away from one side to form an open sided guide passage 106 for the short picket wires. The short picket wires have their ends bent at right angles to the longitudinal axis of the picket, by a mechanism to be hereinafter described,

prior to entering the guide 100 and, therefore, the open-sided guide passage 106 is necessary to permit the passage of the bent end of the picket. Each of the ribs 103 and 104, however, is provided with a plurality of guide dogs 107 which are pivotally secured along the open side of the ribs and normally extend down along the ribs to partially close the open side thereof, and thus aid in guiding the short picket wires. In operation, as the short picket wire moves along the guide 100, the bent end of the picket wire will lift up the successive ones of the dogs 107 and pass thereunder, and the dogs will then fall by gravity again and guide the main body of the picket.

The rotary guide 100 is adapted to be turned or rotated in steps of one-fourth of a revolution, by means of a dog 109 engaging a ratchet 110 formed on one end of the guide. The dog 109 is carried by a bell-crank lever 112 which is operated by a suitable lever 112^a connected to a walking lever 112^b operated by a cam 113 on the shaft 113^a. Shaft 113^a receives its power from the shaft 32 through a pinion 113^b on the shaft 32 which meshes with a gear 113^c on the shaft 113^a. In operation, the short and long pickets are alternated with each other and, therefore, the short and long guide portions or ribs of the guide must be alternately turned into guiding position. The ribs 101 and 102 are diametrically opposite each other and the ribs 103 and 104 are diametrically opposite each other in a plane at right angles to the ribs 101 and 102. Therefore, a one-quarter turn step movement of the guide will present alternately long and short guide ribs for guiding alternately long and short pickets. The movement of the guide 100 is timed to take place in time or simultaneously with the forward movement of the line or cable strands, that is, simultaneously with the movement of the pull-out drum. The simultaneous movement of the guide 100 with the pull-out drum serves to hold the picket wires against the previously formed twists in the advance portion of the line strands as the strands advance and are twisted to the rear of the picket.

A picket cut-off lever 210 is keyed to a short shaft 212 journaled in a bearing bracket 213 on the bed plate of the machine. The lever 210 is adapted to cut the picket wires from the stock after the combined feed and crimp rolls have come to rest. The lever 210 is operated by a cam 214 on the shaft 94, and such cam is so shaped that the operation of the lever is timed to cut the picket wires from the stock simultaneously with or slightly prior to the resting of the feed and crimping rolls and the forward movement of the pull-out drum.

The shaft 212 also carries a cam lever 215 adapted to engage and operate a locking

lever 216 having a locking pin 217 adapted to lock the picket guide 100 against movement.

The cam 215 is so positioned and shaped that it will raise the lever 216 and disengage the locking pin 217 with the start of the shearing stroke of the lever 210 and prior to the rotation of the guide, and will permit the lever 216 and pin 217 to resume its locking position again as the guide 100 comes to rest.

Mounted between the picket feed rollers and the picket guide is a prebender for the short pickets, that is, a mechanism for bending one side of the arch on the short pickets prior to the passage of such pickets through the line wires and picket guide. This short picket prebender consists of a bending head 120 keyed to a vertical shaft 121, which shaft is journaled in a suitable bearing in the bed plate of the machine. The shaft 121 is provided with a suitable sprocket 122 at its upper end above the head 120 which is adapted to be operatively connected by a drive chain 123 with a sprocket 124 on the upper end of a vertical drive shaft 125 also journaled in the bed plate of the machine. The shaft 125 has a beveled gear 126 keyed to the lower end thereof, which gear is in mesh with a gear 127 on a shaft 128. The shaft 128 is adapted to be intermittently operated by a ratchet 129 and racket lock 130 and dog 131. The dog 131 being reciprocated by a connecting rod 132 connected to a crank disk 133 carried by the shaft 78. The ratchets 129 and racket lock 130 are each provided with an equal number of teeth, but each alternate tooth of the lock ratchet 130 is of less depth than the high points on the periphery of the ratchet 129, and the racket lock 130 is adapted to rotate relative to the ratchet 129. The ratchet dog or pawl 131 is of such width that it will engage both the ratchet 129 and lock 130. However, each alternate stroke of the pawl 131 will be a free stroke relative to the ratchet 129, since each alternate tooth in the lock ratchet is above the periphery of the ratchet disk 129. This operation is so timed that the head 120 will operate to bend the short pickets just prior to their movement through the picket guide.

The head 120 is provided with a bending roller 135 mounted on a vertically movable pin 136 which pin is mounted in a recess 137. The pin 136 is reduced at a point below the roller 135 to form a shank portion 138 which projects downwardly through an opening in the head 120 and carries a cam roller 139. A suitable coil spring 140 is mounted around the shank 138 of the pin 136 in the recess 137 and is adapted to be depressed or tensioned when the pin is moved downwardly. A cam ring 141 is mounted on the bed plate of the

machine frame and is so positioned that the roller 139 will ride around the cam when the head 120 is rotated. The cam ring 141 is so shaped and positioned that the pin 136 and roller 135 will be moved downwardly below the top face of the head after the head has rotated sufficiently to form the half arch on the small or short picket so as to ride under the bent picket end and the picket guide, and will be moved or permitted to return to normal position only as it approaches the end of a complete revolution.

After the short picket wires are bent by the head 120 the feed rollers 60 and 61 are automatically set in motion and the picket fed through the picket guide 100 and between the wires of the line strands of the fence. The picket is then cut from the stock by the operation of cut off lever 110.

After the picket has moved into its position between the line wires of the fence, the line wires are twisted, as described herefore, the pull-out drum is then moved forward a step, and the fence is moved forward. As the short picket emerges from under the picket guide, its upper or bent end will enter the space between forming dies 144 and 145. The die 145 is slidable relative to the die 144 and both are supported on a bar or plate 146 which is pivotally mounted on a shaft 147 which is slidably supported in a bearing 148. The forward end of the shaft 147 is connected to a link 149 which in turn is connected to one arm of a crank 150 on a shaft 151, adapted to be periodically rocked and thus pull the shaft 147 and plate 146 together with the dies 144 and 145 forwardly. The shaft 151 is adapted to be rocked by a cam 153 mounted on the shaft 94 and engaging a cam lever 154 on the shaft 151. The cam 153, lever 154 and other parts are so arranged that the forward movement of the forming dies 144 and 145 will take place in time with the forward movement of the fence.

The die 145 is provided with a base portion 155 provided with a ball bearing caster 156 adapted to ride over a stationary cam plate 157. The die 145 is also connected by a universal connection 158 to one end of a link 159 which has its other end connected to one end of a crank 160. The free end of the crank 160 is provided with a roller 161 adapted to be engaged by a cam 162 on the shaft 113^a. The shape of the cam 162, speed of shaft 113^a, shape of cam 157 and the arrangement of these and other associated parts are such that the die 145 will be moved away from the die 144 and down onto a low portion of the cam plate 157 with the return of the dies to their rearward position by a spring 165, and when the dies 144 and 145 are in this position the

dies will be below the plane of the fence. The cam 162 will then act as the short picket enters the space between the dies 144 and 145 to rock the crank 160, thus forcing the die 145 toward the die 144 and 70 also moving the base 155 up over the high portion of cam plate 157 to elevate the dies. This movement bringing the dies together and completing the arch on the short picket, so that the free end of the arch will be in 75 the space in the line wires to receive the next short picket, and such end will then be tied in position by the twisting of the line wires.

The long pickets are adapted to be bent 80 by an entirely different mechanism than the short pickets.

The long pickets are adapted to be fed across the machine through the guide 100 and thence continue through a retracting 85 guide 220 having a flap-like front wall 221 hingedly supported on the main body portion of the guide 220.

The length of the pickets as has been described, is controlled by the cam face 96 on the cam wheel 93. After the long picket is fed across the machine between the line wires, it is trimmed to exact length by a shear consisting of a stationary blade 222 and movable blade 223. The blade 223 is 95 mounted on a rocking lever 224 and operated by a cam 225 on a shaft 94.

Simultaneously with the cutting off of the long picket wire, the spindles 11 are operated to twist the line wires and hold the 100 picket wire in position. As the twisting operation stops, the feed-out roll or drum B will operate to advance the fence, thereby causing the long picket wire to lift up the flap portion 221 of the guide 220 and advance with the remainder of the fence. As the fence advances, the long extended end of the long picket wire forming the stock from which the arch is to be formed will be engaged by one of the fingers 226 of the advancing disk 227 and carried forward into engagement with a placing arm 228 which will place the wire in position between the arch forming rollers 229, 230 and 231.

The advancing disk is mounted on a shaft 232 and is rotated by means of a ratchet wheel 233 mounted on the shaft 232 and engaged by a dog 234 on a rocking lever 235 also mounted on the shaft 232 and rocked by a cam 236 on the shaft 94, through a lever 237 and link 238.

The placing arm 228 is mounted on a short shaft 239 which is adapted to be rocked by a crank lever 240 connected by 125 a link 241 to a rocking lever 242 operated by a cam 243 on the shaft 94.

When the long stay is positioned between the bending or arch forming rollers, the retracting guide 220 is adapted to be moved 130

rearwardly simultaneously, or approximately simultaneously, with the operation of the bending mechanism, so as to clear the end of the picket as it is bent around the 5 in forming the arch. The retracting of the guide 220 is controlled by a cam 245 on the rear end of the shaft 113^a which operates a rocking lever 246 connected to the guide 220 by a link 247.

16 The large roller or die 229 is mounted on a vertically disposed shaft 250 mounted in a suitable bearing in the forward end of a support 251, which support is secured to a reciprocating rack member 252. The 15 lower end of the shaft 250 is provided with a gear 253 which is in mesh with a stationary rack 254 secured to the frame of the machine so as to cause rotation of the shaft 250 and roller 229 when the rack 252 is reciprocated.

17 The rollers 230 and 231 are mounted on the opposite ends of a bell crank 255 which is fulcrumed to the support 251 on the rack 252 at a point coinciding with the axis of the roller 231. The bell-crank 255 is provided with a lug 257 and the rack 252 is provided with an arm 258, and a coil spring 259 is stretched or tensioned between the lug 257 and arm 258 to normally tend to pull or rock said bell crank toward the arm 258 and hold its crank point or elbow against a rigid cam plate 259^a. The cam plate 259 is provided with a main body portion paralleling the rack 252 and at its forward end with an inclined portion 260 which extends forwardly and away from the rack 252, and is provided with a notch 261. The bell-crank 255 is provided with a roller 262 at its elbow adapted to ride on the cam plate 259. The tension of the spring 259 will cause the roller 262 of the bell-crank 255 to ride on the cam plate 259 so that when the rack 252 is in its forward position the roller 262 will be engaged in the notch 261 in the portion of the cam plate, and the roller 230 will be in its farthest position away from the roller 229 so as to permit the straight picket wire to enter between the rollers 229 and 231, as shown in Figure 37.

40 When the rack 252 is moved rearwardly the bell crank will be moved over the cam plate 259, and due to the shape of the plate, the bell crank will be forced to move about its fulcrum point so as to force the roller 230 toward the roller 229 and bend the picket U-shaped, the parts taking the position shown in Figure 39. Simultaneously with the bending of the picket by the rollers 229, 230 and 231 the retracting guide 220 will be retracted to permit the free bending of the picket.

45 The rollers 229 and 231 are provided with gears 265 and 266, respectively, which are meshed, so that when the shaft 250 and roller 229 are rotated due to the movement

of the gear 253 along the rack 254, the roller 231 will also be rotated. The rotation of the rollers 229 and 231 serves to form a permanent set bend in the picket.

50 The rack member 252 which is reciprocated to actuate the long picket bending or arch forming mechanism above described is adapted to be reciprocated by a segmental gear 268 on a shaft 269 which is journaled in brackets 270 and carries a crank lever 271. The crank lever 271 is connected to a crank lever 272 on the shaft 113^a by a connecting rod 273 which is provided with a slip or loss motion connection 274 with the lever 272, which serves to correctly time the operation of the bending mechanism.

55 The operation of the long picket bending or arch forming mechanism is timed so that the end of one picket will be bent after a second picket has been secured in the fence and the line wires are in position to receive a third picket, and the retracting guide will be moved rearwardly simultaneously with the bending operation so as to clear the end of the picket being bent, said guide, however, will have a very quick movement so as to be returned to its guiding or forward position prior to the next picket.

60 While I have shown and described one specific embodiment of my invention, it will be understood that I do not wish to be limited thereto since various modifications in design and construction of the several parts may be made without departing from the scope of my invention as defined in the appended claims.

I claim—

65 1. A machine for making lawn fence having a plurality of spaced line or cable strands, each of which is composed of a plurality of wires twisted together, and spaced picket wires arranged transversely of the line strands and held between the twists thereof, said machine comprising a suitable frame, a pull-out drum on said frame adapted to pull the line or cable strands through the machine, means for revolving said drum with a step-by-step movement with short intervals of rest between each step of movement, means for twisting the line wires during their pulling movement, means for automatically feeding the picket wires between the twists of said line strands, said last-named means including a pair of combined crimping and feeding rolls, a clutch for controlling the operation of said rolls, and a cam and lever mechanism for automatically engaging and disengaging said clutch, said cam disk being provided with adjustable cam faces mounted for adjustment around the periphery of said cam disk so as to vary the length of the cam faces and thereby vary the engagement time of said clutch and thus vary the length of said picket wires.

2. A machine for making lawn fence having a plurality of spaced line or cable strands, each of which is composed of a plurality of wires twisted together, and spaced 5 picket wires arranged transversely of the line strands and held between the twists thereof, said machine comprising a suitable frame, a pull-out drum on said frame adapted to pull the line or cable strands through 10 the machine, means for revolving said drum with a step-by-step movement with short intervals of rest between each step of movement, means for twisting the line wires during their pulling movement, means for automatically feeding alternating short and long picket wires between the twists of said line strands, said last-named means including an elongated rotary 15 guide member arranged transversely of the machine and provided with four longitudinally slotted guide ribs, and means for rotating said guide member one-quarter of a turn simultaneously with each movement of 20 the pull-out drum so as to force and hold the guided picket wire against the previously formed twists in the advance portion of the line strands.
3. A machine for making lawn fence having a plurality of spaced line or cable strands, each of which is composed of a plurality of wires twisted together, and spaced 25 picket wires arranged transversely of the line strands and held between the twists thereof, said machine comprising a suitable frame, a pull-out drum on said frame adapted to pull the line or cable strands through the machine, means for revolving said drum with a step-by-step movement with short intervals of rest between each step of movement, means for twisting the line strands during the forward movements of said pull-out drum and 30 to be at rest when said drum is at rest, means for automatically feeding picket wires between the twists of said line strands during the intervals of rest of said twisting means and said pull-out drum, said twisting means comprising a plurality of twisting spindles, a spindle carrying bar in which said spindles are journaled, a pinion on each of said spindles, a double-faced rack having one face in mesh with said pinions, a mutilated gear in mesh with the other face of said rack, and means for reversely rotating said gear to reciprocate said rack and thereby reversely 35 rotate said twisting spindles.
4. A machine for making lawn fence having a plurality of spaced line or cable strands, each of which is composed of a plurality of wires twisted together, and spaced 40 picket wires arranged transversely of the line strands and held between the twists thereof, said machine comprising a suitable frame, a pull-out drum on said frame adapted to pull the line or cable strands through the machine, means for revolving said drum with a step-by-step movement with short intervals of rest between each step of movement, means for twisting the line strands during the forward movements of said pull-out drum and 45 to be at rest when said drum is at rest, means for automatically feeding picket wires between the twists of said line strands during the intervals of rest of said twisting means and said pull-out drum, said twisting means comprising a plurality of twisting spindles, a spindle carrying bar in which said spindles are journaled, a pinion on each of said spindles, a double-faced rack having one face in mesh with said pinions, a mutilated gear in mesh with the other face of said rack, and means for reversely rotating said gear to reciprocate said rack and thereby reversely 50 rotate said twisting spindles.
5. A machine for making lawn fence having a plurality of spaced line or cable strands, each of which is composed of a plurality of wires twisted together, and spaced 55 picket wires arranged transversely of the line strands and held between the twists thereof, said machine comprising a suitable frame, a pull-out drum on said frame adapted to pull the line or cable strands through the machine, means for revolving said drum with a step-by-step movement with short intervals of rest between each step of movement, means for twisting the line strands during the forward movements of said pull-out drum and 60 to be at rest when said drum is at rest, means for automatically feeding picket wires between the twists of said line strands during the intervals of rest of said twisting means and said pull-out drum, said twisting means comprising a plurality of twisting spindles, a spindle carrying bar in which said spindles are journaled, a pinion on each of said spindles, a double-faced rack having one face in mesh with said pinions, a mutilated gear in mesh with the other face of said rack, and means for reversely rotating said gear to reciprocate said rack and thereby reversely 65 rotate said twisting spindles.

ervals of rest between each step of movement, means for twisting the line strands during the forward movements of said pull-out drum and to be at rest when said drum is at rest, means for automatically feeding picket wires between the twists of said line strands during the intervals of rest of said twisting means and said pull-out drum, said twisting means comprising a plurality of 10 twisting spindles, a spindle carrying bar in which said spindles are journaled, a pinion on each of said spindles, a double-faced rack having one face in mesh with said pinions, a mutilated gear in mesh with the other face of said rack, right and left-hand ratchet teeth on said gear, ratchet dogs adapted to engage said teeth, means for operating said dogs to rotate said gear, and means for alternately rendering said dogs inoperative so that said gear will be rotated in opposite directions to reciprocate said rack and thereby reversely rotate said twisting spindles.

7. A machine for making lawn fence having a plurality of spaced line or cable strands each of which is composed of a plurality of wires twisted together, and spaced picket wires arranged transversely of the line strands and held between the twists thereof, said machine comprising a suitable frame, a pull-out drum on said frame adapted to pull the line or cable strands through the machine, said drum comprising a central shaft revolvably mounted in suitable bearings in said frame, a plurality of supporting disks keyed on said shaft, longitudinal bars secured to said disks to form a cage-like drum, a plurality of pairs of gripping jaws mounted on said bars, one of each of said pairs of jaws being pivoted for movement toward and away from the other jaw of the pair, said pivoted jaws being normally held away from said other jaws in open position, and cam-operated means for moving said pivoted jaws toward said other jaws at predetermined points in the path of rotation of said drum to cause said jaws to grip the line or cable strands of the fence, ratchet wheels on said central shaft of said drum, bell-crank rocker arms carried by said shaft, dogs mounted on said arms and engaged with said ratchet wheels, and cam means for rocking said arms to cause said dogs to rotate said ratchet wheels and said drum with a step-by-step movement, means for twisting the line strands during the forward movements of said drum and to be at rest when said drum is at rest, and means for automatically feeding picket wires between the twists of said line strands.

8. A machine for making lawn fence having a plurality of spaced line or cable strands, each of which is composed of a plurality of wires twisted together, and spaced picket wires arranged transversely of the line strands and held between the twists thereof, said machine comprising a suitable frame, a pull-out drum on said frame adapted to pull the line or cable strands through the machine, means for feeding picket wires between the twists of said line strands of the fence, means for revolving said drum with a step-by-step movement, means for twisting the line strands during the forward movements of said drum and to be at rest when said drum is at rest, and means for automatically feeding picket wires between the twists of said line strands.

9. A machine for making lawn fence having a plurality of spaced line or cable strands, each of which is composed of a plurality of wires twisted together, and spaced picket wires arranged transversely of the line strands and held between the twists thereof, said machine comprising a suitable frame, a pull-out drum on said frame adapted to pull the line or cable strands through the machine, said drum comprising a central shaft revolvably mounted in suitable bearings in said frame, a plurality of supporting

disks keyed on said shaft, longitudinal bars secured to said disks to form a cage-like drum, a plurality of pairs of gripping jaws mounted on said bars, one of each of said pairs of jaws being pivoted for movement toward and away from the other jaw of the pair, said pivoted jaws being normally held away from said other jaws in open position, and cam-operated means for moving said pivoted jaws toward said other jaws at predetermined points in the path of rotation of said drum to cause said jaws to grip the line or cable strands of the fence, ratchet wheels on said central shaft of said drum, bell-crank rocker arms carried by said shaft, dogs mounted on said arms and engaged with said ratchet wheels, and cam means for rocking said arms to cause said dogs to rotate said ratchet wheels and said drum with a step-by-step movement, means for twisting the line strands during the forward movements of said drum and to be at rest when said drum is at rest, and means for automatically feeding picket wires between the twists of said line strands.

9. A machine for making lawn fence having a plurality of spaced line or cable strands, each of which is composed of a plurality of wires twisted together, and spaced picket wires arranged transversely of the line strands and held between the twists thereof, said machine comprising a suitable frame, a pull-out drum on said frame adapted to pull the line or cable strands through the machine, means for twisting the line wires, means for feeding picket wires between the twists of said line strands, and means for guiding said picket wires across said machine, said last-named means including an elongated rotary guide member arranged transversely of the machine and provided with four longitudinal slotted guide ribs, and means for rotating said guide member one-quarter of a turn after each picket is placed in the line strands so as to force and hold the guided picket wire against the previously formed twists in the advance portion of the line strands.

10. In a machine for making lawn fence having a plurality of spaced line or cable strands, each of which is composed of a plurality of wires twisted together, and spaced picket wires arranged transversely of the line strands and held between the twists thereof, means for bending the top ends of at least some of said pickets to form arches and to insert the free end of the bent portion between the twists of said line strands, said means comprising an advancing disk adapted to force the extended end portion of the picket wire from which the arch is to be formed forward into engagement with a placing arm, means for automatically rocking said placing arm to force the end

of said picket wire between suitable forming rollers, and means for automatically operating said rollers to bend the end of said picket wire to form an arch.

- 5 11. In a machine for making lawn fence having a plurality of spaced line or cable strands, each of which is composed of a plurality of wires twisted together, and spaced picket wires arranged transversely of the line strands and held between the twists thereof, means for bending the top ends of at least some of said pickets to form arches and to insert the free end of the bent portion between the twists of said line strands, 10 said means including a prebending head adapted to bend said picket wires before said wires are positioned between the wires of said line strands, said head comprising 15 a rotary body having an anvil portion there-

on, a bending roller on said body portion and adapted to engage the picket wires to be bent and bend said picket wires around said anvil portion at right angles, means for automatically disengaging said bending roller from said picket wires, and a pair of forming dies adapted to engage the prebent portion of said picket wires after they are in position between the wires of said line strands, one of said dies being reciprocable relative to the other and adapted to be reciprocated to force said prebent picket wire against the other forming die to complete the formation of the arch, and means for automatically operating said dies.

In witness whereof I have hereunto signed my name.

JOHN A. COCKER.
